UNITED STATES PATENT OFFICE.

CHRISTOPHER H. LONERGAN, OF ENSLEY, ALABAMA.

MINER'S-CHECK PROTECTOR.

1,322,912.

Specification of Letters Patent. Patented Nov. 25, 1919.

Application filed March 12, 1919. Serial No. 282,119.

To all whom it may concern:

Be it known that I, CHRISTOPHER H. LONERGAN, a citizen of the United States of America, residing at Ensley, in the county 5 of Jefferson and State of Alabama, have invented certain new and useful Improvements in Miners'-Check Protectors, of which the following is a specification.

This invention relates to an improvement 10 in miners' car check holders adapted for attachment to mine cars.

The object of my invention is to provide a simple and durable device which will receive and hold the check of the miner loading 15 the car to which the device is attached so as to prevent the substitution of another check while at the same time providing for the ready removal of the check at the tipple.

More particularly my invention contemplates 20 the provision of a gravitating slide normally disposed in position to hold a check against removal and yet which is so disposed that the operator on the tipple can readily shift it into position in which it will 25 permit the check to fall where it can be easily removed.

My invention also involves the novel details of construction and arrangements of 30 parts, which in their preferred embodiments only are illustrated in the accompanying drawings which form a part of this specification, and in which:—

Figure 1 is a partial sectional view of a mine car showing my appliance mounted 35 therein in vertical cross section.

Fig. 2 is a bottom plan view of the outer casing of the device.

Fig. 3 is an enlarged sectional view of the 40 device showing the sliding guard in elevated position; and

Fig. 4 is a sectional view taken on the line A—A of Fig. 3.

Similar reference numerals refer to similar parts throughout the drawings.

I have illustrated my invention as applied 45 to a mine car 1 which is typical of any mine car. Preferably the device is attached within the car and comprises a vertically disposed casing 2 having therein a cylindrical chamber 3 which opens through its bottom 50 wall and extends to a point near the top wall of the casing. The casing is provided with a check admission slot 4 at a downward

inclination of approximately 45° into the upper inner side wall of the chamber 3 and 55 having its inlet opening in the vertical side wall of the casing. On the opposite side of the chamber 3 from the slot 4 and at the base of the chamber I provide a slot 5 registering with a hand hole 6 in the side wall 60 of the car, this slot and hole having a width approximately equal to the diameter of the chamber 3 and sufficient for the ready insertion of the fingers of the tipple operator therethrough so that the latter can have access to the chamber 3 to operate the sliding check guard 7 that is vertically movable in 65 said chamber. This guard 7 is preferably formed by a section of metal pipe having in its upper end a vertical guide slot 8 in which 70 a pin 9 in the casing works so as to prevent the rotation of the guard. A section of the upper inner side wall of the guard is removed so as to form a notch 10 having its top wall lying in a plane parallel with the 75 plane of the check slot 4 and having its bottom wall preferably at right angles to the long axis of the chamber 3. The lower half section of the front guard wall is cut away at 11, leaving a notch having its side walls 80 12 lying in a vertical diametric plane and its top wall 13 lying in a horizontal plane at right angles to the walls 12 and normally disposed about half way between the bottom 14 of the car and the top of the slot 5 and 85 hole 6, as will be seen more clearly in Fig. 1. In this position the notch 10 is out of register with the slot 4 and the pin 9 stands near the top of the guide slot 8. A check 90 15 having been deposited in the slot 4 before the car is loaded will stand in the dotted line position shown in Fig. 3 with its lower end resting against the top of the tubular guard 7 and far enough above the notch 10 in the latter to insure that the jolting of 95 the car will not accidentally raise the notch into register with the slot 4 and thus permit the loss of the check in transit. To remove the check, the tipple operator thrusts his finger through the registering openings 5 100 and 6 and catches the top wall 13 of the guard notch 11 and raises the latter to the level of the top of the openings 5 and 6, as shown in Fig. 3. This brings the notch 10 into register with the slot 4, thereby permitting 105 the check to fall through the tubular

guard onto the bottom 14 of the chamber 3 where the tipple operator can readily grasp it and withdraw it through the openings 5 and 6. The arrangement of the device is such that it is practically impossible, after removal of the check, to insert a new one into the slot 4 and retain it there until the slide can be brought back to normal position. In other words, my appliance will 10 prevent the substitution of checks but will present no appreciable difficulty to the ready removal of the check.

The casing 2 is preferably made in the form of a metallic casting having the chamber 3 and slot 4 molded therein and also having side lugs or ears 16 for the reception of the screws or bolts 17 by which the casing is attached within the car.

Though the preferable point of attachment of the casing is within the car it is obvious that it may be disposed without the car. While I prefer to use the tubular guard as shown, it will be obvious that any form of sliding guard which is so shaped as in normal position to close the slot 4 and in raised position to permit the check to fall from the slot 4 into the position in the casing to be accessible for removal while at the same time preventing access to the slot 4 to substitute a check, will accomplish the purposes of my invention.

This invention is not intended to be restricted in scope to the specific embodiments shown, but contemplates such modifications as come within the spirit and scope of the claims.

Having thus described my invention, what I claim as new and desire to secure by Letters Patent, is:—

40 1. A miner's check protector comprising a casing having a slide chamber with check admission and discharge openings at opposite ends thereof, and a vertically movable gravitating slide normally disposed to close the check admission opening and having a part thereof accessible from without the casing for shifting it, said slide having a passage way therein which, when the slide is lifted, stands in position for the check to 45 pass therethrough from the check admission slot to an exposed position opposite said discharge opening.

2. A miner's check protector comprising a casing having a slide chamber with check admission and discharge openings at opposite ends thereof, and a hollow gravitating slide normally disposed to close the check admission opening and having a part thereof accessible from without the casing for shifting it, said slide having a passage way through which when the slide is shifted, the check passes from said admission opening to an exposed position opposite said check discharge opening.

3. A miner's check protector comprising 65 a casing having a slide chamber opening through its bottom and provided with a check admission slot entering its upper side portion and a check removal slot opening through its lower opposite side portion, a 70 sliding check guard vertically adjustable in said chamber, means to prevent the rotation of said guard which has a check passage on its inner side adapted, when the guard is raised, to register with the check admission 75 slot, and means accessible through the check removal slot for raising the guard, substantially as described.

4. In a miner's check protector, a casing having a cylindrical chamber opening 80 through its bottom and closed overhead, there being in its upper side a check admission slot and in its bottom opposite side a check removal slot, a tubular check guard movable in said cylindrical chamber, guide 85 means to prevent the rotation of said guard, there being a notchout in the upper side of said guard disposed normally below and out of register with said check admission slot, and there being a notchout in the opposite 90 lower side of said guard registering with the check removal slot in the casing, substantially as described.

5. In a miner's check protector, a casing having a vertical cylindrical chamber opening through its bottom and closed overhead, there being in its upper side a check admission slot and in its bottom opposite side a check removal slot, a tubular check guard movable in said cylindrical chamber, 95 guide means to prevent the rotation of said guard, there being a notchout in the upper side of said guard disposed normally below and out of register with said check admission slot, and there being a notchout in the 100 opposite lower side of said guard registering with the check removal slot in the casing, the top wall of said latter slot in the guard standing normally spaced substantially the same distance below the top of the check removal slot in the casing that the upper notch in the guard stands below registering position with the check admission slot in the casing.

6. In a miner's check protector, the combination with a mine car, of a casting seated on the bottom of the car and attached to the side wall thereof, there being a cylindrical chamber extending vertically from the bottom to a point near the top of said casting, and there being a check admission slot entering the upper inner side of said casting and a check removal slot entering the lower outer side of said casting, said car having a slot registering with said latter 120 slot in the casting, a section of metal pipe 125 vertically adjustable in said cylindrical chamber in the casting, and guide means to

prevent the rotation of said pipe, there being an upper notch in the inner side of said pipe adapted when it is raised to register with the check admission slot in said casting, 5 and the lower outer half of said pipe being cut away to leave a notch having a top edge normally exposed below the tops of said

check removal slots in the ear and castings, as and for the purposes described.

In testimony whereof I affix my signature. 10

CHRISTOPHER H. LONERGAN.
